(57) **CLAIM**

The ornamental design for an automated teller machine, as shown and described.

DESCRIPTION

The combined shape and figure of the automated teller machine is claimed as the main point of creation in the design application.

FIG. 1 is a perspective view.

FIG. 2 is a front view.

FIG. 3 is a rear view.

FIG. 4 is a left side view.

FIG. 5 is a right side view.

FIG. 6 is a plan view.

FIG. 7 is a bottom view; and,

FIG. 8 is a perspective view in an open position thereof, the undisclosed portions are not part of the claimed design.
